ATTORNEY.

UNITED STATES PATENT OFFICE.

JAY P. KNIGHT, OF ONONDAGA VALLEY, NEW YORK.

TOOL FOR SURFACING RAZOR-STROPS.

SPECIFICATION forming part of Letters Patent No. 712,811, dated November 4, 1902.

Application filed July 5, 1902. Serial No. 114,340. (No model.)

To all whom it may concern:

Be it known that I, JAY P. KNIGHT, a citizen of the United States, and a resident of Onondaga Valley, in the county of Onondaga, 5 in the State of New York, have invented new and useful Improvements in Tools for Surfacing Razor-Strops, of which the following, taken in connection with the accompanying drawings, is a full, clear, and exact description.

15 o This invention relates to the class of tools which are employed for applying to the surfaces of razor-strops a coating which expedites the operation of sharpening razors thereon and serves to produce a keener and finer edge on the razor.

The object of this invention is to provide a tool of the aforesaid class which shall be more efficient and convenient in its operation and capable of being readily repaired or adjusted to be supplied with different surfacing material; and to that end the invention consists in the novel construction of the tool hereinafter described, and set forth in the claims.

In the annexed drawings, Figure 1 is a side 25 view of a tool embodying my invention. Fig. 2 is a longitudinal section of said tool, and Fig. 3 is a transverse section on line X-X in Fig. 1.

a represents the handle of the tool. The 30 upper end of this handle has firmly secured to it a plate b, disposed at right angles to the axis of the handle and provided with a central perforation c and with perforations c' c' at opposite sides of the center.

35 d d represent the strop-surfacing bars, which are disposed parallel side by side and are each composed of material of a different degree of hardness—i. e., one may be composed of zinc and the other of lead or other suitable mate-

40 rial. The softer of said bars is designed to apply an abrading-surface to the razor-strop by rubbing the said bar upon the strop. The bar of the harder material is to be subsequently employed in a similar manner to 45 smoothen said abrading-surface on the strop, or both bars may be used simultaneously. The said surfacing-bars d d are secured at one end to the handle by means of studs e e, projecting from the ends of the bars and in-

50 serted into the perforations c' c' in the plate b. Through the central perforation c of said plate projects a tie-rod f, which is firmly se-

cured in the handle a and passes between the bars d d and has its free end screw-threaded and extending beyond the adjacent ends of 55 the bars d d. A cap g is provided with a perforation h in its center and with perforations h' h' at opposite sides of said center. Through the central perforation protrudes the end of the tie-rod f, while the studs e e on the ends 60 of the bars d d enter into the perforations h' h'. Said cap thus fastens the free ends of the bars d d to the tie-rod f. A nut n, applied to the protruding end of the tie-rod and bearing on the cap g, serves to confine the said 65 cap in its engaging position.

The surfacing-bars d d may be of the form of cylindrical tubes having stay-rods passing longitudinally through them and protruding through the ends thereof to form the aforesaid studs e e. Grooves i i in the sides of the bars d d, engaging the tie-rod f, prevent said bars from turning.

The described construction of the surfacing-tool allows the surfacing-bars d d to be 75 readily removed for repairs or renewal when required, said removal merely requiring the nut n to be unscrewed from the tie-rod f and the cap g to be stripped from said rod. This allows the bars d d to be drawn out of engagement with the plate b.

What I claim as my invention is—

1. The improved tool for surfacing razor-strops, which consists of a plurality of surfacing-bars disposed side by side and each 85 composed of a strop-surfacing material of a different degree of hardness, a handle secured to one end of the joined bars, a tie extending from the handle to the free ends of the bars, and a cap securing said ends of the bars to 90 the tie as set forth.

2. A tool for surfacing razor-strops, consisting of a plurality of bars disposed side by side and formed with transversely-rounded faces and each composed of strop-surfacing 95 material of a different degree of hardness, a handle secured to one end of the joined bars, a tie-rod extending from the handle and passing between the said bars, and a cap tying the free ends of the bars to the said rod as 100 set forth.

3. A tool for surfacing razor-strops, consisting of a handle, a plate affixed to said handle at right angles to the axis thereof and

provided with a plurality of perforations, a tie-rod fastened to the handle and projecting through the central perforation of the plate, surfacing-bars disposed parallel at opposite 5 sides of the tie-rod and provided with studs inserted in perforations of the aforesaid plate, a cap having perforations receiving the end of the tie-rod and adjacent studs of the surfacing-bars, and a nut on the protruding end 10 of the tie-rod confining the cap in its engagement as set forth.

4. A tool for surfacing razor-strops, consisting of a plurality of tubes disposed side by side and each composed of metal of a dif-

ferent degree of hardness, stay-rods passing 15 longitudinally through said tubes and protruding at the ends thereof, a handle having affixed to it a plate perforated to receive the protruding ends of the stay-rods at one end of the joined tubes, a tie-rod extending rigidly from the handle and passing between the tubes, and a cap secured to the free end of the tie-rod and perforated to receive the adjacent ends of the stay-rods as set forth. 20

JAY P. KNIGHT.
